(57) **CLAIM**

The ornamental design for a vehicle, as shown and described.

DESCRIPTION

FIG. 1 is a right front perspective view of a vehicle showing my new design;

FIG. 2 is a left rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a right front perspective view of a second embodiment of a vehicle showing my new, with the interior of the vehicle shown in broken lines which form no part of the claimed design;

FIG. 9 is a left rear perspective view of the vehicle shown in FIG. 8.

FIG. 10 is a left side view thereof.

FIG. 11 is a right side view thereof.

FIG. 12 is a front view thereof.

FIG. 13 is a rear view thereof.

FIG. 14 is a top view thereof.

FIG. 15 is a right front perspective view of a third embodiment of a vehicle showing my new, with the top of the vehicle in a closed position.

FIG. 16 is a left rear perspective view of the vehicle shown in FIG. 15.
